UNITED STATES PATENT OFFICE.

WILLIAM J. KENNEDY, OF SOMERVILLE, MASSACHUSETTS, ASSIGNOR TO DERBY DESK COMPANY, OF SOMERVILLE, MASSACHUSETTS, A CORPORATION OF MAINE.

DESK-LOCK.

No. 897,467.

Specification of Letters Patent.

Patented Sept. 1, 1908.

Application filed April 3, 1908. Serial No. 424,863.

To all whom it may concern:

Be it known that I, WILLIAM J. KENNEDY, a citizen of the United States, residing at Somerville, in the county of Middlesex and 5 State of Massachusetts, have invented a new and useful Improvement in Desk-Locks, of which the following is a specification.

The invention relates to a lock for locking roll top desks, and consists of a mechanism 10 actuated by one of the drawers below the desk top, preferably the middle drawer, above the leg space, which eliminates the necessity of a lock in the roll of the top, as heretofore universally used.

15 In the drawings, Figure 1 is a front view of a desk with part of the desk broken away to show the locking mechanism, and its relation to the different parts of the desk. In this form of the invention the actuating bar is below the slide leaf. Fig. 2 is an enlarged section of one side of the desk, showing the same construction as that in Fig. 1. Fig. 3 is a top plan of the invention. Fig. 4 is a top plan of a section of the actuating bar in the 20 recess or cam of the drawer which actuates it. Fig. 5 is a cross section of a pilaster showing the mortise through which the actuating bar passes to the side of the desk. Fig. 6 is a modification of Fig. 1, in which the actuating bar is above the slide leaf and in a mortise in the under side of the desk top. Fig. 7 is an enlarged section showing one side of the desk having the same construction as that of Fig. 6.

35 In the drawings, Figs. 1 and 2, the spring catch 2 is fastened by the screws, 3, in the groove or track for the roll of the top. The wood behind the spring catch, 2, is cut away so as to provide a space, 4, to permit the 40 spring catch to move back. This space is extended down through the desk top and into the pilaster to permit a lever extension, 5, of the spring catch to play in. A groove, 6, extends from the space, 4, in the top of the partition between the slide leaf and the drawer below it, and through the pilaster next to the middle drawer. In this groove the actuating bar, 7, is slidably located, the outer end of which rests against the lower end of the 45 spring catch, 5, and the inner end rests in a cam mortise, 8, in the drawer, as clearly shown in Figs. 2, 3, and 4, when the drawer

is closed, being forced there by the spring pressure of the spring catch, 2. A mortise, 9, is cut in the end of the roll-board, over 55 which a keeper, 10, is fastened. Into this keeper the bolt or hook, 11, springs when free to do so, when the roll top is closed, and securely locks the roll top down to the desk top. In order to unlock the top it is only 60 necessary to pull out the middle drawer when the cam of the mortise, 8, rides against the end of the actuating bar, 7, and forces the bolt, 11, out of the keeper, 10, thereby unlocking the roll top. The inner end of the 65 actuating bar, 7, which works in the mortise, 8, is turned at right angles to its flat side, and rolled on the end, as shown in Fig. 4, so as to prevent wearing the mortise and the drawer side against which it presses. 70

In Figs. 3 and 6, the actuating bar, 7, is shown in a mortise, 13, in the underside of the desk top. This slight modification, however, requires a slight bend, 14, of the actuating bar, 7, near its inner end, as shown. 75

It will be seen that not only is this mechanism cheap and effective, but it eliminates necessity for a lock in the roll top, and that the lock in the middle drawer together with the mechanism herein shown, suffices to lock 80 it and the roll top.

While I show a locking bar on both sides of the desk, one would ordinarily answer the purpose.

It will be noted that the latch or bolt 11 85 normally tends to move into locking position and by the action of the spring it is yieldingly moved to such position, and by the action of the drawer when the latter is moved outwards, the bolt or latch is positively moved to unlatching position, and as a result of this feature of my invention, it will be seen that the drawer may be fully closed and locked without first closing the roll top, and afterwards the latter may be 90 closed and when it reaches its full shut position, the latch or bolt yieldingly pressing against the edge of the roll top will automatically, from its normal tendency, move into locking position when the mortise 9 comes 100 opposite the latch or bolt. This independence of the roll top and the drawer is of importance because it is not necessary to leave the drawer unlocked or partially open while

using the top of the desk, or if the drawer be fully closed and locked, to unlock and open it before the roll top can be closed and locked.

What I claim is:

5. 1. In a roll-top desk, the combination of a roll top, a latch or bolt situated to engage the roll top at the side thereof and situated above the desk top and contiguous thereto at the front thereof, an opening and closing member of the desk situated below the desk top, and a latch or bolt operating means adapted to be moved by said opening and closing member and extending horizontally therefrom at the front of the desk and beneath the upper surface of the desk top to the latch or bolt.
10. 2. In a roll-top desk, the combination of a roll top, tracks for the side edges of said top, a latch or bolt situated in one of the tracks to interlock with the track-engaging portion of the roll top, yieldingly held in interlocking engagement, an opening and closing member of the desk, and means interposed between said member and the latch or bolt
15. 25. that positively moves the bolt or latch to unlocking position when said opening and closing member of the desk is moved to an open position, said means permitting movement of said member to closed position independently of the position of the latch or bolt.
20. 3. In a roll top desk, the combination of a roll top, tracks engaged by the edges thereof, a spring actuated latch or bolt situated in one of the tracks and normally tending to
25. 35. locking position, a drawer having a surface

inclined with reference to the direction of movement of the drawer, and a bar adapted to engage said inclined surface and connected with the latch or bolt.

4. In a lock for roll top desks, the combination of a spring catch located in the track of the roll top, and having a lever with a downward extension through the desk top, a rod below the desk top to actuate said lever extension, and a cam in a drawer below the desk top to actuate said rod.

40. 5. In a lock for roll top desks, the combination of a spring catch located in the track of the roll top with a lever extension therefrom, a keeper on the lower end of the roll top to coöperate with the said spring catch, a rod below the desk top to actuate the said lever extension, and a cam in a drawer below the desk top to actuate said rod.

45. 6. In a lock for roll top desks, the combination of a spring catch, with a downward lever extension located in each of the two roll top tracks, one on the right and the other on the left side, and two rods below the desk top to actuate the lever extensions, and 50 two cams in the middle drawer below the desk top, one on the right and the other on the left side of said drawer.

In testimony whereof I affix my signature in presence of two witnesses.

WILLIAM J. KENNEDY.
